INVENTOR
JOHN H. HICKEY.
BY *Arthur H. Gleas*
ATTY.

UNITED STATES PATENT OFFICE.

JOHN H. HICKEY, OF SAN FRANCISCO, CALIFORNIA.

RENEWABLE FUSE.

Application filed August 5, 1926. Serial No. 127,336.

My invention relates to improvements in fuses wherein a fusible conductor of predetermined current carrying capacity is rendered readily observable without removal 5 from a fuse block, and wherein renewal may be effected by replacing an inner transparent shell only.

The primary object of my invention is to provide an improved fuse.

10 Another object is to provide an improved fuse wherein the fusible conductor is rendered readily observable without weakening the fuse housing and without endangering workmen in inserting or removing fuses.

15 A further object is to provide an improved device of the character described, wherein the fusible conductor is carried within an inner filler shell detachably enclosed within an outer covering, whereby

20 the fuse may be renewed by replacing the inner shell only.

Another object is to provide an improved construction which will facilitate and permit an efficient evacuation of the fuse shell 25 whereby the fuse may be operated in vacuum.

A further object is to provide an improved construction which will facilitate the sealing of the conductor within the fuse.

30 A still further object is to provide an improved construction which may be economically manufactured and which will effect a substantial saving in renewal costs.

I accomplish these and other objects by 35 means of the improved device disclosed in the drawings forming a part of the present application wherein like characters of reference are used to designate similar parts throughout the specification and drawings 40 and in which,

Fig. 1 is a side elevation of my improved fuse.

Fig. 2 is a longitudinal section of the fuse.

Fig. 3 is an end elevation of the fuse, and

45 Fig. 4 is a transverse section taken upon the line 4—4 of Fig. 2.

Referring to the drawings, my improved fuse will be seen to consist of a filler shell 1 formed from glass or other suitable transparent material. The shell 1 is tubular in form and is provided with annular shoulders 2 formed adjacent the ends thereof by indenting the shell inwardly, as best shown in Fig. 2 of the drawings.

50 Pans 3 having flaring edges are fitted against the outer sides of the shoulders 2.

Conductors 4 are carried by the pans 3, said conductors having their inner ends extending axially inward to spaced relation within the shell 1. The outer ends of the conductors 4 extend outwardly through the pans 3 to points substantially flush with the ends of the shell. A fusible conductor 6 is secured between the spaced inner ends of the conductors 4, said conductor being designed to carry a predetermined current.

The outer ends of the conductors 4 are connected to contact plates 7 fitted flush with the ends of the shell 1 and preferably having an offset center portion apertured to receive the ends of the conductors 4 and to permit said conductor ends to be soldered upon the outer surfaces of the plates. The space between the plates 7 and the pans 3 at each end of the shell 1 is filled with a suitable cementitious material 5, preferably litharge and glycerine, adapted to effectively seal the plates 7 and the conductors 4 within the ends of the shell 1. A tip 9 is formed within one of the indentations of the shell 1, whereby the shell may be evacuated. The tip 9 is formed at a point spaced at a considerable distance from the conductor, thereby permitting the tip to be heated for sealing the tube after the air is drawn out without affecting the fuse conductors.

A cover 11 is fitted around the shell 1 to reinforce and strengthen the same and to prevent breakage of the shell when being inserted or removed from a fuse block. The cover is cylindrical in shape and arranged to fit closely around the shell along the entire length thereof. The cover is formed for any suitable non-conductive material and has openings 12 formed in the sides thereof at points opposite the fusible conductor 6, whereby said conductor may be readily observed through the transparent shell.

Caps 14 are fitted over the ends of the shell 1 and cover 11. The caps are made of conductive material and arranged to form contact with the contact blades of a fuse block, the type illustrated in the drawing being provided with contact blades 16 of the form commonly used in fuses designed to carry high power currents. The caps 14 are detachably secured by means of suitable securing elements carried by the plates 7, preferably bolts 17 having their heads 18 soldered or otherwise secured in connection with the plates 7 and arranged to extend outwardly through suitable openings formed in

the caps, whereby suitable nuts 19 may be applied to detachably hold the caps in firm contact with the outer surfaces of the plates 7. The caps engage the plates 7 along a relatively wide annular surface, thereby insuring an efficient electrical connection through the caps to the conductors 4.

In operation, the fuse, constructed and assembled as above described, is applied and 10 operates in the usual manner, in so far as the conducting of electric current is concerned. The apertured cover combined with the transparent shell 1 permits the fuse to be observed without removing the same from 15 a fuse block. This is of material advantage, as a single glance will determine at once whether or not the fuse has been blown and in this manner greatly facilitates the checking up of the fuses and the locating of blown 20 fuses.

In the event a fuse is blown, my improved construction permits renewal by merely replacing the shell 1. This is accomplished by 25 loosening the nuts 19 and removing the caps 14. The shell 1 may then be readily removed from the cover 11 and a new shell inserted. The old caps are then replaced and the fuse is again ready for use. In 30 practice, the shells are made in standard sizes to fit different sizes of fuse blocks and are designed to fit the covers and caps provided for the particular size of fuse. The fillers may be manufactured at a relatively 35 low cost and by providing for the replacement of the filler shell alone a material saving is effected in renewal costs. At the same time, the covers 11 insure a strength and ruggedness suited to any ordinary usage.

40 The provision of a glass filler shell sealed at the ends in the manner above described is of importance also, because of the fact that the shell may be readily evacuated. When air is present within the fuse body 45 the fusible conductor becomes oxidized and the current carrying capacity is thereby affected. By exhausting the air from the shell, this oxidization is avoided and the capacity of the conductor is maintained constant when in use. The evacuating of the 50 fuse is also important, because of the fact that it prevents a sudden expansion of air, such as might otherwise burst the fuse shell. The tip 9 through which the air is exhausted 55 is positioned within one of the indentations formed upon the shell, thereby obtaining sufficient space between the tip and the conductor to prevent said conductor from becoming damaged by the heat applied in sealing the shell and also preventing the possible 60 breakage due to expansion around the sealed end of the shell. The cement applied between the plates 7 and caps 3 affords an efficient sealing which may be easily and 65 cheaply accomplished without the necessity

of fusing the shell itself upon the conductors or other metal at any point.

While I have illustrated and described what I now regard as the preferred construction of my invention, the device is subject 70 to modification in numerous ways without departing from the spirit of the invention. I therefore do not wish to restrict myself to the specific construction illustrated and described, but desire to avail myself of all 75 modifications which may fall within the scope of the appended claims.

Having thus described my invention what I claim as new and desire to secure by Letter's Patent is,

1. A fuse comprising a shell; a fusible conductor mounted within the shell and extending longitudinally therethrough; contact plates mounted within the ends of the shell in connection with the ends of the conductor; means for sealing the ends of the shell around the conductor and plates to permit the shell to be evacuated; a detachable cover enclosing the shell; and means for detachably retaining the cover upon the shell, said means being adapted to form electrical connection between the contact plates and a fuse block.

2. A fuse comprising a transparent shell; a fusible conductor mounted within the shell and extending longitudinally therethrough; contact plates mounted within the ends of the shell in connection with the ends of the conductor; means for sealing the ends of the shell around the conductor and plates to permit the shell to be evacuated; a detachable cover enclosing the shell and having openings formed in the sides thereof, whereby the fusible conductor may be observed through the transparent shell; and means for detachably retaining the cover upon the shell, said means being adapted to form electrical connection between the contact plates and a fuse block.

3. A fuse comprising a transparent shell; a fusible conductor mounted within the shell and extending longitudinally therethrough; contact plates mounted within the ends of the shell in connection with the ends of the conductors; means for sealing the ends of the shell around the ends of the conductor and the contact plates to permit the shell to be evacuated; a detachable cover enclosing the shell and having openings formed in the sides thereof, whereby the fusible conductor may be observed through the transparent shell; caps fitted over the ends of the shell and cover, said caps being arranged to form electrical contact between the contact plates and a fuse block; and means carried by the contact plates and engaging the caps for detachably retaining the caps and cover upon the shell.

4. In a renewable fuse, a filler comprising a transparent shell; annular shoulders

indented into the shell adjacent the ends thereof; pans fitted against the outer sides of said shoulders; a fusible conductor extending longitudinally through the shell and extending outwardly through the pans; plates fitted within the ends of the shell and connected to the ends of the conductor; and a cement filling set within the ends of the shell between the pans and the plates to seal the ends of said shell, whereby the same may be evacuated.

5. In a renewable fuse, a filler comprising a transparent shell; annular shoulders indented into the shell adjacent the ends thereof; pans fitted against the outer sides of said shoulders; a fusible conductor extending longitudinally through the shell and extending outwardly through the pans; plates fitted within the ends of the shell and connected to the ends of the conductor; and a cement filling set within the ends of the shell between the pans and the plates to seal the ends of said shell, whereby the same may be evacuated; and an apertured cover detachably secured around the shell, whereby the fusible conductor may be observed, said cover being adapted to permit renewal of the fuse by replacing the filler only.

6. In a renewable fuse, a filler comprising a transparent shell; annular shoulders indented into the shell adjacent the ends thereof; pans fitted against the outer sides of said shoulders; conductors connected to each pan and extending axially into spaced relation within the shell and having their outer ends extending outwardly through the pans; a fusible conductor of predetermined current carrying capacity secured between the inner ends of the conductors; plates fitted within the ends of the shell and connected to the ends of the conductors; and means for sealing the ends of the shell, whereby the same may be evacuated.

7. In a renewable fuse, a filler comprising a transparent shell; annular shoulders in-

dented into the shell adjacent the ends thereof; pans fitted against the outer sides of said shoulders; conductors connected to each pan and extending axially into spaced relation within the tube and having their outer ends 50 extending outwardly through the pans; a fusible conductor of predetermined current carrying capacity secured between the inner ends of the conductors; plates fitted within the ends of the shell and connected to the 55 ends of the conductors; and means for sealing the ends of the shell, whereby the same may be evacuated; and an apertured cover detachably secured around the shell, whereby the fusible conductor may be observed 60 through the transparent shell, said cover being adapted to permit the renewal of the fuse by replacing the filler only.

8. In a renewable fuse, a filler comprising a transparent shell; annular shoulders indented into the shell adjacent the ends thereof; pans fitted against the outer sides of said shoulders; conductors connected to each pan and extending axially into spaced relation 65 within the tube and having their outer ends 70 extending outwardly through the pans; a fusible conductor of predetermined current carrying capacity secured between the inner ends of the conductors; plates fitted within the ends of the shell and connected to the 75 ends of the conductors; and means for sealing the ends of the shell, whereby the same may be evacuated; an apertured cover detachably secured around the shell, whereby the fusible conductor may be observed 80 through the transparent shell; caps fitted over the ends of the cover and shell and arranged to form electrical contact between the contact plates and a fuse block; and means carried by the contact plates and detachably engaging the caps, whereby the fuse 85 may be renewed by replacing the filler only.

In witness whereof, I hereby set my signature.

JOHN H. HICKEY.
